UNITED STATES PATENT OFFICE.

LUD HOLLAND-LETZ, OF OAK PARK, ILLINOIS, ASSIGNOR TO INTERNATIONAL HARVESTER COMPANY OF NEW JERSEY, A CORPORATION OF NEW JERSEY.

PLATFORM-LATCH FOR REAPERS.

1,275,689.

Specification of Letters Patent. Patented Aug. 13, 1918.

Application filed March 22, 1916. Serial No. 85,909.

To all whom it may concern:

Be it known that I, LUD HOLLAND-LETZ, a citizen of the United States, residing at Oak Park, in the county of Cook and State 5 of Illinois, have invented certain new and useful Improvements in Platform Latches for Reapers, of which the following is a full, clear, and exact specification.

My invention relates to platform latches 10 for reapers.

It has for its object to improve these latches in such a manner as to enable the platform of a reaper to be attached to the stub axle thereof with greater certainty and 15 with greater facility. A more specific object of my invention is to improve the attaching means by which the platform is attached to the stub axle after the reaper platform has been lowered to operative position, 20 in such a manner that the parts may not be accidentally left in unattached position by a careless operator. I attain these objects by providing an improved arrangement and construction of attaching means, the same 25 being carried upon the platform at a point adjacent the pivot thereof and above the end of the stub axle and operable from the top of the reaper platform with a certain definite movement.

30 In order that my invention may be clearly and fully disclosed, I have illustrated one embodiment thereof in the accompanying drawings.

In these drawings:

35 Figure 1 shows a reaper of standard construction equipped with my improvement, the reaper platform being shown in its operative position in full lines and in its inoperative position in dotted lines;

40 Fig. 2 is a detail plan view of the mechanism on the upper surface of the reaper platform;

Fig. 3 is a sectional view taken substantially on lines 3—3 of Fig. 2 looking in the 45 direction of the arrow, the parts being in attached position;

Fig. 4 is a detail view taken substantially on line 4—4 of Fig. 3 looking in the direction of the arrow;

50 Fig. 5 is a bottom sectional view taken substantially on line 5—5 of Fig. 3, the parts being in detached position.

The reaper shown is of standard construction, including a frame 1 having the usual 55 reaper head 2 thereon, the frame being

mounted upon a main wheel 3 and having the usual reaper platform 4 pivotally connected thereto at 5 so that this platform may be raised to the dotted or inoperative position shown in Fig. 1. As in the usual 60 construction, a transport wheel 6 is mounted upon a stub axle 7 beneath the outer end of this platform, and an adjustable leg or support 8 is also carried upon the frame 1 at a point substantially beneath the pivot 65 of the platform, which leg is movable into supporting position prior to the lifting of the platform. A second stub axle 9 is also carried upon the frame 1 and protrudes laterally beneath the platform 4 so that, in 70 preparing the machine for transport, the wheel 6 may be removed from its stub axle 7 and placed thereon after the platform has been braced in its raised position. As usual, of course, the leg 8 is thrown up after the 75 wheel has been placed upon the axle 9.

In my improved construction a bracket having a horizontally disposed tubular member 10 is fixed to the underside of the platform 4, and this tubular member is provided 80 with a lower cut-away portion 11 so that when the platform is lowered the member 10 may rest upon the end of the axle 9. Within this tubular member is carried a sleeve member 12 of substantially rectangular cross section and having an open top at one end thereof adapted to be reciprocated in the member 10 so that its open topped end 13 passes under and alongside the end of the axle and with member 10 holds the platform 85 and stub axle securely together, as shown in Fig. 3, inwardly extending lugs 14 being provided in the member 12 to limit the movement thereof relative to the axle. As illustrated in Figs. 3 and 5, this member 12 is 90 provided with a rack surface 15 at one side thereof meshing with a pinion 17 which extends through the open side 18 in the upper surface of the member 12, and this pinion 17 is provided with a sleeve portion 19 journaled in the upstanding sleeve 20 preferably formed integral with the member 10. Carried in a suitable recess 21 in the upper end of this member 19 is a coiled spring 22 which normally presses upward the short end of 105 an operating or adjusting member 23, which is pivoted on a transverse pivot at a point intermediate its ends, as at 24, to the member 19. As shown, the opposite end of this operating member 23 is provided with a lat- 110

erally extending handle 25 slightly curved in such a manner as to facilitate grasping of the same by an operator. Coöperating with the upstanding lug 26 on the short end of this member 23 is a top plate 27 preferably formed integral with the member 19 and resting on the upper surface of the platform. As shown, this plate 27 has a slot 28 provided therein so arranged as to permit the short projection carrying arm of the member 23 to be depressed therein when the handle 25 has been raised. The platform 4 is provided with a circular opening 29 to permit free rotary movement of the member 19. Disposed above all of this slot 28, except a portion at each end thereof, is an overlying plate 30 attached to the top of the platform and preferably having a raised semi-circular guiding portion 31 thereon engageable with the lug 26 and limiting the upward movement thereof by the spring 22 until the member 23 has been rotated to such an extent as to move the member 13 to one of its limits in the open side 18 of the member 12, when the spring will force the lug 26 upward and automatically lock the parts in position.

In the operation of the device, when the platform 4 is lowered into the down position shown in full lines in Fig. 1, the member 13 is in the retracted position shown in Fig. 5. All that it is then necessary to do to throw the member 13 into holding position, wherein it connects the platform and the axle, is to rotate the member 23, whereupon, through the pinion 17, the member 13 will be reciprocated into its axle engaging position shown in Fig. 3. It will be noted that when the member 23 is in the unlocked position, as shown by dotted lines in Fig. 2, the spring 22 is compressed, the lug 26 being held down by the portion 31, and that when the rack member completes its normal movement, this lug 26 on the member 23 has passed out from under the portion 31 of the plate 30 so that the lug may be projected into locking position by the spring and the handle 25 lowered automatically as soon as it is released, as shown by full lines in said figure. Obviously, by the use of such a device, whenever the member 23 may not be moved through its normal complete movement, the operator will know that for some reason there is not the proper registry of the member 13 and the stub axle and will take steps to correct the trouble before the machine is moved forward in the field. The member 13 and the stub axle 9 are shown in Fig. 5 in proper registry for the correct operation of the device.

In connection with my improved construction, attention is also directed to the fact that the adjusting means is very conveniently located, access being had to the same from the top of the platform. It is also to be

noted that the entire mechanism is so seated in the platform as to be substantially flush therewith and not interfere with the progress of the grain. Obviously, my improved mechanism may also be very cheaply manufactured and so ruggedly constructed as to be exceedingly durable in service.

While I have in this application specifically described one embodiment which my invention may assume in practice, it is, of course, to be understood that this form of the same is used for purposes of illustration and that the invention may be modified and assume other forms without departing from its spirit, it being my intention to include all such modifications within the scope of the appended claims.

What I claim as new is:

1. In a reaper, a frame, a reaper platform thereon, a stub axle disposed beneath said platform, means for attaching said axle to said platform and operating means therefor carried on the upper surface of said platform.

2. In a reaper, a frame, a reaper platform thereon, a stub axle disposed beneath said platform, a reciprocating axle engaging member carried beneath said platform, and operating means therefor carried on the upper surface of said platform.

3. In a reaper, a frame, a reaper platform thereon, a stub axle disposed beneath said platform, a reciprocating axle engaging member carried beneath said platform, and operating means therefor including a rotatable operating member normally disposed substantially flush with the surface of said platform.

4. In a reaper, a frame, a reaper platform thereon, a stub axle disposed beneath said platform, a reciprocating sleeved rack member engageable with said axle and carried on the bottom of said platform, a pinion engaging said rack member, and means for rotating the pinion from the top of said platform.

5. In a reaper, a frame, a stub axle thereon, a platform having a member carried in the bottom thereof disposed above the end of said axle, a member reciprocable in said member under the end of said axle, and means including rack and pinion mechanism operable from the top of said platform for reciprocating said member.

6. In combination, a frame, an adjustable platform thereon, a support extending beneath said platform, a movable attaching member on said platform engageable with said support, and means for positively operating said attaching member to lock said platform in operative position on said support, said operating means having a predetermined movement and being completely operable to attach said platform to said support only when said support and said at-

taching member are in register with each other.

7. In combination, a frame, an adjustable platform thereon, a support extending beneath said platform, a movable attaching member on said platform engageable with said support, positive operating means therefor having a predetermined movement and completely operable to attach said platform to said support only when said support and said attaching member are in register with each other, and means for normally holding said operating means at one of the ends of its limit of movement.

15 8. In a reaper, a frame, a stub axle thereon, a platform carried on said frame, a rack member having a sleeve portion projectable longitudinally of said axle, a pinion engageable with said rack member and having an upwardly extending body portion, an operating member pivoted on said body portion and rotatable therewith, and resilient means normally holding said operating member in a predetermined position.

25 9. In a reaper, a frame, a stub axle thereon, a platform carried on said frame, a rack member having a sleeve portion projectable longitudinally of said axle, a pinion engageable with said rack member and having an upwardly extending body portion, and an operating member pivoted thereto and rotatable therewith normally disposed substantially flush with the upper surface of said platform.

35 10. In a reaper, a frame, a stub axle thereon, a platform carried on said frame, a rack member on said platform having a sleeve portion projectable longitudinally of said axle, a pinion engageable with said rack member and having an upwardly extending body portion, a rotatable operating member

for said pinion pivoted thereto, said operating member having a projection thereon, means holding one end of said member depressed after movement of the same about 45 its pivot and during a part of the rotation thereof, and means normally holding said projection in projected position.

11. In a reaper, a frame, a stub axle thereon, a platform disposed above said axle, a bracket member fixed to said platform having a horizontal sleeve portion and a vertically disposed sleeve portion, an axle supporting rack member reciprocable in the horizontal sleeve portion of said bracket, a pinion journaled in the vertically disposed sleeve portion of said bracket, and means operable from the upper surface of said platform and connected to said pinion and movable about a pivot in said platform for 50 rotating said pinion and thereby projecting said sleeved rack member toward or from the end of said axle.

12. In a reaper, a frame, a stub axle thereon, a platform connected to said frame 65 disposed above said axle, said platform having a recess therein, a sleeved rack member carried on said platform projectable under the end of said axle, a pinion member engageable with said rack member, a rotatable 70 operating member operable from the top of said platform and pivoted to said pinion member at a point intermediate its ends, a co-operating guiding member carried on said platform disposed over one end of said operating member during a part of the rotation thereof, and means for projecting the depressed end of said member upward when it passes beyond said guiding member.

In testimony whereof I affix my signature. 75

LUD HOLLAND-LETZ.
